STOOL TO SUPPORT MOLDS FOR CASTING METAL

Charles H. Aldrich, Elizabeth, N. J., assignor, by mesne assignments, to The American Metal Company, Limited, New York, N. Y., a corporation of New York

Application January 2, 1935, Serial No. 84

15 Claims. (Cl. 22—139)

This invention relates to improvements in metal stools adapted for use in casting metal, and more particularly to improvements in stools constructed of copper or suitable copper alloy to be used as a support for a mold to be employed in the casting of steel ingots.

It has been the practice in the past to cast steel ingots in molds supported on cast-iron stools constructed in the form of a single unit. These stools were unsatisfactory because of imperfections which developed therein due to the relatively poor thermal conductivity of the metal and the resulting strains in and distortions of portions of the stool occasioned by local expansion of parts in contact with or closely adjacent the molten metal in the mold and also to the fact that the surface of the stool is gradually eroded away by the stream of molten steel, resulting in the early destruction of the stool.

As an improvement upon unitary stools made of cast iron, resort was had to single massive stools of copper. Such stools were to some extent more satisfactory than the cast-iron stools in view of the relatively greater thermal conductivity of the copper which dissipated the heat energy from parts immediately under the highly heated metal in the mold to underlying and surrounding portions of the stool, thus to some extent reducing the local distortion of portions of its surface and resulting imperfections.

Notwithstanding the advantages of the unitary massive copper stool, its life is greatly shortened by the formation of surface cracks, particularly in cases of stools of large dimensions. The parts of the stool immediately under the steel as it is poured into the ingot mold are caused to rapidly expand while confined by surrounding and underlying portions which are relatively cool. The expanded portion is caused to bulge upwardly since it is closely confined in all other directions. As the heat energy is conducted from this expanded portion to the surrounding and underlying portions of the stool, they in turn expand, and at the same time the originally heated and distorted portion from which heat is being dissipated must contract. These violent opposing forces tend to tear the surface portion of the stool apart and produce gaps and fissures which grow larger and larger as the stool is successively used. These surface cracks or fissures soon become of a size such as to permit molten steel poured into the ingot mold to enter and firmly secure the ingot being cast to the stool, thus clearly indicating that the stool has become unfit for further service. The

rate of such deterioration due to surface cracking of one-piece copper stools increases very rapidly as the horizontal dimensions of the stool are increased.

It is an object of this invention to provide a stool which will be far more economical to construct than the one-piece stools herein referred to, but which will provide for free local expansion of portions of the stool immediately underlying the molten metal poured into a mold supported on its surface, and thereby reduce the tendency to distort and crack its surface and render it unfit for service.

The invention consists generally in the dividing of the stool, or at least the surface portion of the stool, into a number of sections separated by crevices extending from its mold bearing surface towards its base, the construction being such that the sections will either be slightly separated by fissures of an appreciable width, with their surfaces out of contact, or such that the sections may readily readjust themselves by movement in a direction perpendicular to the crevices as they are expanded by increase of temperature during a casting operation.

The feature of dividing the stool into a number of sections with provisions for free local expansion would constitute a very material improvement in any stool whether constructed of cast iron, copper, or any other appropriate metal, but the best results may be obtained by applying this new feature to a stool made of copper, copper alloy, or any other metal having a relatively high thermal conductivity.

Important features of the invention not heretofore mentioned include means for providing free air circulation about the metal sections of the stool to rapidly dissipate heat; means whereby the sections may be readily assembled in, held in place, and removed from, a supporting and confining frame, means whereby the sections may be yieldingly held in the frame with their surfaces in snug contact, and the use of sections of shapes such that they may be interchangeably assembled in various positions, thereby materially increasing their effective life.

In the accompanying drawings illustrating the preferred and various modified forms of the above-described invention,—

Figure 1 is a plan view of a stool comprising a plurality of sections assembled in a frame and held in place by the use of wedges.

Fig. 2 is a view, partly in side elevation and partly in longitudinal section, of the form of the

invention illustrated by Fig. 1, the plane of the section being represented by the line 2—2.

Fig. 3 is a plan view of a form of the invention in which springs, rather than wedges, are used as 5 a means of yieldingly holding the sections of the stool in their assembled relation in a frame.

Fig. 4 is a large-scale view, partly in side elevation and partly in longitudinal section, of the form of the invention illustrated by Fig. 3, the 10 plane of the section being represented by the line 4—4.

Fig. 5 is a plan view of a form of the invention which differs from the form illustrated by Figs. 1 and 2 in that special means are provided for 15 air circulation.

Fig. 6 is a view, partly in side elevation and partly in longitudinal section, of the form of the invention illustrated by Fig. 5, the plane of the section being indicated by the line 6—6.

20 Fig. 7 is a transverse sectional view of the stool illustrated by Figs. 5 and 6, the plane of the section being represented by the line 7—7 of Fig. 5.

Fig. 8 is a plan view of a stool which differs from the one illustrated by Figs. 1 and 2 in that 25 it is adapted to support two molds at the same time.

Fig. 9 is a plan view of a stool the sections of which are in the form of cubes which may be interchangeably assembled in various positions.

30 Fig. 10 is a perspective view of one of the cubes of the stool represented by Fig. 9.

Fig. 11 is a fragmentary plan view of a circular stool having the invention embodied therein.

Fig. 12 is a cross-sectional view of the stool 35 illustrated by Fig. 11.

The form of the invention illustrated by Figs. 1 and 2 may comprise a plurality of metal sections 20 mounted in a metal frame 21 comprising side walls 22, end walls 23 and a base 24. The 40 frame may be of dimensions such as to accommodate the sections when assembled in a snug side-to-side relationship, and the sections may be held in close contact with each other in the frame by any appropriate means, such, for example, as the wedges 25.

Although the invention is not intended to be limited to the use of any particular metals, the frame may preferably consist of cast iron and the sections 20 of copper or some suitable alloy of copper.

55 It is now possible to cast copper in vertical molds of relatively great height as compared with their cross-sectional dimensions, the resulting castings, which may be referred to as V. C. cakes, being of substantially uniform dimensions from end to end. Such cakes may now be cast with sufficient accuracy to be used as the sections of stools constructed in accordance with this invention, by merely cropping their upper ends and placing them on edge in the frame, the width of the cake constituting the depth of the stool.

If desired, the cakes may be of slightly greater thickness at their centers than at their edges so as to provide crevices between the sections at 65 the upper mold supporting surface of the stool, as indicated at 26, and by correspondingly flaring the opposite edges of each section, the section may be inverted after one of its working surfaces has been rendered unfit for service, thus 70 increasing its period of usefulness.

If the sections are flared as indicated in Figs. 1 and 2, so as to provide open crevices extending downwardly a material distance from the mold supporting surface of the stool, the sections may 75 be held in the frame by relatively unyielding

wedges which may be constructed of cast iron or steel, since the open crevices at the surface of the stool afford the desired free space for local expansion.

The width of the crevices as illustrated in Figs. 5 1 and 2 is somewhat exaggerated. Such width need be only great enough to provide for the increase in thickness of the surface portions of the sections of the stool when expanded during a casting operation, and, when so apportioned, it 10 has been found that the crevices need not be of a width such as would permit the molten steel to enter during the pouring of a casting. If desired, however, the crevices may be closed by painting the surface of the stool with a thin 15 coating of fire clay, or other suitable inert material, which would be sufficiently soft to permit the sections to expand while acting as a seal against the entrance of molten steel.

In Figs. 1 and 2 the position of the bottom portion of an ingot mold supported by the stool is diagrammatically indicated in broken lines, the wall of the mold being indicated at 27 and the casting cavity at 28.

It will be apparent that when molten metal is 25 poured into the mold 27, the underlying surface portion of the stool will be rapidly heated, as a result of which the upper surface portions of the underlying sections 20 will be expanded and increased in thickness, but this expansion will 30 merely tend to close the open crevices 26 until the local temperature has been reduced by conduction of the heat energy to the underlying and surrounding parts of the stool and dissipated by radiation and convection. The depth of the stool 35 should be such that it may dissipate the heat energy absorbed during a casting operation without being subjected to a dangerous temperature. A temperature of from 700° to 800° Fahrenheit is not regarded objectionable. In the casting of 40 steel ingots of some considerable size it has been found that if the stool is made of copper sections a depth of twelve inches is quite satisfactory. For very large castings a somewhat greater depth of stool might, perhaps, be used to advantage. 45

As a precautionary measure which might tend to increase the life of the stool and prevent any possibility of trouble due to the cutting of its surface by the molten metal at the commencement of the pouring of a casting before a sufficiently 50 deep pool of metal has accumulated in the bottom of the mold to serve as a protection, a relatively thin steel plate 29 may be placed on the surface of the stool at the bottom of the mold cavity before the metal is poured. The plate 55 need not extend over the entire area of the mold bottom but should cover so much of the surface of the stool as may be necessary to prevent the poured metal from impinging directly against the surface of the copper during the initial part 60 of the pouring operation. The plate should be no thicker than required to serve its intended purpose of protecting the surface of the stool, and if properly proportioned will be melted and entirely merged into and become a part of the 65 steel ingot.

In Figs. 3 and 4 is illustrated a form of the invention which differs from that illustrated by Figs. 1 and 2 in that the sections 20^a, which are mounted in the frame 21^a, are not represented 70 as having their marginal portions flared so as to provide open crevices along the surface of the stool. In this form of the invention, although the crevices 26^a between the sections are closed, provision for expansion is made by the use of 75

springs 25^a, instead of wedges, as a means of holding the sections in their assembled relation in the frame. The springs 25^a may be confined between a metal header 30 in contact with the 5 end sections of the stool and spring seats 31 which may be held in their spring confining positions by means of threaded bolts 32 and nuts 33, the bolts being extended through openings in, and the nuts seated against, the end wall 23^a of 10 the frame.

The header 30 of the form of the invention illustrated by Figs. 3 and 4 may be provided with a shield or canopy 34 to overhang the springs and their associated elements and prevent 15 metal, dust or other foreign material from making its way around and between the parts of the spring mechanism and interfering with its usefulness.

Preferably the sections 20^a may be slightly 20 shorter than the internal width of the frame 21^a so as to provide open air gaps 35 along the sides 25 of the sections, and a series of openings 36 may be provided in the sides of the sections to permit air to enter and pass through the gaps 35 and dissipate heat energy imparted to the sections 30 during a casting operation.

When metal is poured into the casting cavity 28 of a mold 27 supported on the stool illustrated by Figs. 3 and 4, the heat energy imparted to the 30 sections 20^a through the metal plate 29, if used, will cause the sections to expand, and since the 35 crevices 26^a are closed crevices, the walls of which are in contact with each other throughout the entire depth of the stool, the expansion will cause the sections to spread out along the length of the frame 21^a and re-distribute themselves, such adjustment being permitted by the yielding of the 40 springs 25^a. After the casting of the ingot, the heat in the stool will be dissipated by radiation and convection, and, as the sections resume their 45 normal dimensions, the springs 25^a will cause them to be returned to their normal positions and held snugly against each other in readiness for another casting operation.

The form of the invention illustrated by Figs. 5 to 7, inclusive, differs from those heretofore described in that the frame 21^b, within which the sections are mounted, has a base in the form of 50 spaced bars 24^b upon which the sections 20^b may be supported, and section confining elements or walls 22^b, 23^b, separated slightly from the outer surfaces of the sections so as to provide intervening gaps 35^b for the circulation of air, the lower margins of the walls 22^b, 23^b being spaced 55 above the level of the under surfaces of the supporting bars 24^b so that the walls will be separated from the surface of any support on which the frame may be placed and thereby permit air to enter and pass upwardly through the gaps 35^b 60 and cool the sections of the stool during and after a casting operation.

In the form of the invention illustrated by Figs. 5 to 7, inclusive, as distinguished from the form illustrated by Figs. 1 and 2, the mold supporting sections 20^b are held in the frame by take-up means in the form of wedges 25^b of wood or other appropriate material between both of the 65 end sections of the stool and the adjacent walls 23^b of the frame, so that air gaps may be provided between the sections and both end walls as well as between the sections and the side walls. 70 Obviously the provision of air gaps or channels between the outer surfaces of any of the mold supporting sections and adjacent surface portions of the frame is not dependent upon the 75

character or location of the springs, wedges or other take-up devices used to hold the sections in close association.

It will be apparent that when using any one of the three forms of stool thus far described, any 5 section or sections the surfaces of which become unfit for further service may be readily removed and inverted or interchanged with one at the end of the frame or replaced by a new section, by merely removing the wedges if the stool is one 10 of the form illustrated by Figs. 1 and 2 or Figs. 5, 6 and 7, or by unscrewing the bolts 32 sufficiently to render the holding springs 25^a ineffective if the stool is one of the form illustrated by 15 Figs. 3 and 4. The stool is, therefore, not only capable of being manufactured at relatively small expense, but the maintenance cost is also relatively small for the reason that each section of the stool may be used until it is unfit for further service, irrespective of the condition of other 20 sections, whereas in the case of a solid stool if one small area becomes unfit for use the whole stool must be scrapped.

In Fig. 8 is illustrated a form of the invention which indicates that the stool may readily be 25 made of a size such as to support a plurality of casting molds. When making such a multiple stool, if the material of the mold supporting sections is relatively expensive as compared with that of the frame, it is not necessary that 30 the entire frame be filled with such relatively expensive sections. The mold supporting sections may be confined to the parts of the stool on which the molds are intended to rest, and the intervening space or spaces may be filled in 35 with some less expensive material. In Fig. 8, for example, two sets of sections 20^c are assembled in a frame 21^c in positions such as to be adapted to support two casting molds 27^c. These sections, which might be constructed of copper 40 or copper alloy, might be separated by a single intervening section 37, and this intervening section and the frame in which it and the copper sections are assembled might be of cast iron. The entire series of sections, including the copper 45 sections and the intervening cast-iron section, might be kept in close contact with each other and with one end of the frame by any appropriate take-up means such, for example, as the wedges 25^c driven into spaces between the 50 wall at the opposite end of the frame and the adjacent surfaces of the sections. Such a multiple stool might conform as to details of construction of its parts with other forms of stool heretofore described. 55

In Figs. 9 and 10 is illustrated a form of the invention which differs from that illustrated by Figs. 1 and 2, for example, in that the sections 20^d may be in the form of cubes which may be held in an assembled relation in a frame 21^d by 60 means of wedges or other appropriate holding means 25^d, which may be inserted at the ends of the transversely disposed series of sections as well as at the ends of the longitudinally disposed series. As best indicated by Fig. 10, the 65 four marginal portions of each of the six faces of each cube may, if desired, be slightly inclined so that, when the cubes are assembled in the frame, the faces which form the mold supporting surface of the stool will be separated by two 70 series of open crevices intersecting each other at right angles, and, since the cubes are symmetrical as to all three of their axes, they may not only be readily shifted from one part of the frame to another, but may also be used with each 75

of their six similar faces uppermost until all six surfaces have been rendered unfit for further use.

It is not essential that the relative sizes of the various faces of the sections conform with any of those which have been illustrated by way of example. They need not be in the form of cubes, as illustrated by Figs. 9 and 10, nor need they be of a length such as to extend across the entire width of the supporting frame as illustrated by Fig. 5, or even half way across the frame as illustrated by Figs. 1, 3 and 8. They should be of a depth sufficient to avoid overheating and their other dimensions should bear such a relation to the joints by which they are separated from each other as to avoid undue distortion of their upper surface portions when heated during a casting operation.

The form of the invention illustrated by Figs. 1 and 2 has been disclosed as one involving stool sections having slightly flared upper edges so as to provide crevices along the upper surface of the stool, and the sections are disclosed as being held in close contact with each other by metal wedges 25 driven into spaces between the end sections and an adjacent wall of the supporting frame. The form of the invention illustrated by Figs. 3 and 4 has been disclosed as one comprising copper sections having parallel side faces so as to fit quite closely together and be separated by closed joints, the sections being held in contact with each other by springs inserted between the end sections and an adjacent wall of the supporting frame. In the form of the invention illustrated by Figs. 5 to 7, inclusive, the device is disclosed as one having copper sections with closed joints held in close association with each other by wedges which may be of wood or other appropriate material. The form of the invention illustrated by Figs. 9 and 10 is disclosed as one having sections with slightly flared surface portions to produce open joints at the surface of the stool, the sections being held in close association by appropriate fastening means which might be springs or wedges of metal or wood. In making these various disclosures it has been indicated that when relatively unyielding fastening means, such as metal wedges, are used, it might be preferable to use copper sections having flared surfaces such as to produce open joints at the surface of the stool, and that when sections having parallel plane side surfaces are used, such as to produce substantially closed joints at the surface of the stool, it would be preferable to use springs or wedges of yielding material, such as wood, as a means of holding the sections in close association. It has been found, however, that even when steel wedges are used as the means for keeping the copper sections of the stool in close contact with each other, and even when such sections have substantially plane parallel side surfaces and substantially closed joints at the upper surface of the stool, the sections are still free to yield sufficiently to take care of surface expansion due to slight irregularities in the joints even though they have previously been wedged together tightly enough to prevent steel from entering the joints. If, therefore, the dimensions of the metal sections are properly proportioned with respect to the joints, metal wedges, wooden wedges and spring-holding means may be interchangeably used as means for keeping the sections in close association irrespective of whether or not the lateral surfaces of the sec-

tions are flared to produce open crevices at the surface of the stool.

In Figs. 11 and 12 is illustrated a form of the invention which might be so expensive to construct as to be impractical. It serves, however, as an illustration of one of the many forms in which the generic principle of the invention may be applied. It consists of a circular stool comprising a frame 21^c having a base 22^c consisting of a series of annular section seats 38 and a 10 circular central seat 39 at different levels and a plurality of sections 20^c supported on said seats, comprising a central cylindrical section surrounded by concentric annular sections. The sections may be of dimensions such that they will fit 15 rather loosely within the shoulders 40 surrounding their seats, the inner and outer diameters of the sections being such as to leave intervening annular crevices of sufficient width to allow for expansion. Although the construction is such 20 that the various rings may not be held in an accurately concentric relation, the shoulders surrounding the seats for the sections will prevent the rings from becoming materially displaced, and the working clearances allowed between the 25 rings and the shoulders surrounding the seats, as well as the clearances between the rings to allow for expansion, may be such that the rings might be cast and used without machining, or the metal may be drawn or extruded into cylinders of considerable length and cut to sizes required in making the stool. The gradation in the depth of the rings is such as to provide the greatest depth of metal at the center of the stool where the need for absorbing and dissipating 35 heat is greatest.

It will be apparent from the foregoing description and the accompanying drawings that the word "crevice" is used throughout this application in its broad sense such as would include 40 either an open crevice having its walls out of contact or what might be called a closed crevice amounting to nothing more than a dividing zone between two parts having complementary surfaces in contact with each other. 45

It will also be apparent that the widths of the crevices between the sections of the forms of the invention illustrated by Figs. 1, 2, 9, 11 and 12 are grossly exaggerated. They need be no greater than is necessary to provide for expansion due to 50 heating during a casting operation, and by making the sections of the stool sufficiently narrow the crevices may be of widths such that the metal poured in an overlying mold will not enter.

If desired, the support for the copper mold 55 sections may be provided with mold centering lugs and pads for properly positioning the stool upon a truck, such as are commonly applied to cast-iron stools. Such pads and lugs might be applied to the supporting frame of any of the 60 forms of stool herein disclosed. As illustrated for example in Figs. 1 and 2, the frame may be provided at the four corners of its upper surface with centering lugs 41 so located as to properly 65 position the mold when supported on the stool. Likewise, the under surface of the supporting frame may be provided with pads 42 to enter depressions of like dimensions in the surfaces of trucks by which the mold may be supported and transported from one position to another. The pads 42 on the mold frame and the depressions in the surfaces of the trucks serve as a means of definitely positioning one with respect to the other. The possibility of applying such centering 70 lugs and pads to any of the stools disclosed in 75

this application constitutes an important feature of the invention which could not be practicably applied to stools constructed in the form of a single massive slab of copper.

5 5 The invention is not intended to be limited to the specific forms which have been selected for purposes of illustration, but should be regarded as including modifications and variations thereof within the scope of the appended claims.

10 10 What is claimed is:—

1. A metal stool for an open-bottomed ingot mold adapted for use in casting metal, said stool comprising a composite, mold-supporting structure consisting of numerous, relatively small sections separated by crevices extending from its upper surface to its base and means for holding said sections assembled with their adjacent surfaces in close association.

2. A stool, as defined by claim 1, of which the 20 component sections are constructed of copper.

3. A stool, as defined by claim 1, of which the component sections are constructed of an alloy of copper.

4. A stool, as defined by claim 1, of which the 25 crevices between the sections are vertical and mutually parallel.

5. A stool, as defined by claim 1, of which the crevices between the sections, when cool, are open at and for a considerable distance below the 30 mold supporting surface to an extent such as to allow for free expansion of the heated parts of the stool during a casting operation.

6. A stool, as defined by claim 1, of which the 35 crevices between the sections are vertical and mutually parallel, and of which the means for holding the sections in an assembled relation include means for forcing the end sections towards each other and for maintaining the forcing means effective whereby each section of the series, 40 intermediately the end sections, is compressed and snugly held between a pair of adjacent sections.

7. A stool, as defined by claim 1, of which the 45 opposed side surfaces of the sections are flared slightly along their opposite edge portions so as to produce narrow open gaps between the sections extending along the opposite surfaces of the stool when the sections are held in close contact with each other along the zones of their opposed surfaces intermediate their flared portions.

8. A stool, as defined by claim 1, of which the 50 means for holding the sections in an assembled relation comprises a rigid, open-topped frame of a size such as to accommodate the assembled sections and wedging means to set up mutually opposed forces between the sections and adjacent parts of the frame, whereby the sections may be held compressed in close contact with each other and with the section confining portions of the section holding means.

9. A stool, as defined by claim 1, of which the 55 means for holding the sections in an assembled relation comprises a rigid, open-topped frame of a size such as to accommodate the sections and

expansive resilient means to set up mutually opposed forces between the sections and adjacent parts of the frame, whereby the sections may be yieldingly held compressed in close contact with each other and with the section confining portions of the section holding means. 5

10. A stool, as defined by claim 1, of which the means for holding the sections in an assembled relation comprises a rigid, open-topped frame of a size such as to accommodate the sections, expansive resilient means to set up mutually opposed forces between the sections and adjacent parts of the frame, whereby the sections may be yieldingly held compressed in close contact with each other and with the section confining portions 15 of the section holding means, and means for adjusting the tension of the resilient means. 10

11. A stool, as defined by claim 1, of which the sections are in the form of cubes separated by two series of vertical crevices, the crevices of one series being perpendicular to those of the other. 20

12. A stool, as defined by claim 1, of which the sections are in the form of cubes separated by two series of vertical crevices, the crevices of one series being perpendicular to those of the other, 25 and each of the cubes being slightly flared along each of the four marginal portions of each of its six faces, so that the cubes may be interchangeably used with any of their faces up and invariably cooperate to produce a chequered mold supporting surface having portions which are equally 30 expansible in all directions.

13. A stool, as defined by claim 1, of which the means for holding the sections in an assembled relation include an open-topped frame of dimensions such as to accommodate the assembled sections and leave gaps between outer surface portions of the sections and adjacent walls of the frame, the walls of the frame which extend along the gaps being slotted to provide for a circulation of air to cool the sections during a casting 40 operation. 35

14. A stool, as defined by claim 1, of which the means for holding the sections in an assembled relation includes an open-topped frame having 45 spaced base members to support the sections and side section confining members in spaced relation with outer surface portions of the sections so as to provide passages for air circulation, the lower margins of the confining members being above 50 the lower level of the base members so as to space the confining members from a supporting surface on which the frame may rest and thereby provide for the admission of air to the passages 55 between the sections and their confining members.

15. A stool, as defined by claim 1, having a plurality of sectional mold supports, and intervening spacing material which need not be of the 60 same character as that of the sections of the supports.

CHARLES H. ALDRICH.
